US00D618194S

(12) United States Design Patent
Kim et al.

(10) Patent No.: US D618,194 S
(b4) Date of Patent: * Jun. 22, 2010

(54) PORTABLE TELEPHONE

(75) Inventors: Jin-Soo Kim, Kyunggi-do (KR);
Min-Hyouk Lee, Seoul (KR);
Seog-Guen Kim, Seoul (KR)

(73) Assignee: Samsung Electronics Co., Ltd.,
Kyunggi-Do (KR)

() Term: 14 Years

(21) Appl. No.: 29/312,490

(22) Filed: Oct. 23, 2008

(51) LOC (9) Cl. 14-03

(52) U.S. Cl. .... D14/138 AA

(58) Field of Classification Search D14/341-347,
D14/147, 496, 203.3, 203.4, 203.7, 138 AA,
D14/138 R, 138 AD; 455/575.1, 575.4, 556.2

See application file for complete search history.

(57) CLAIM

The ornamental design for a portable telephone, as shown and described.

DESCRIPTION

FIG. 1 is a top front perspective view of a portable telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
